UNITED STATES PATENT OFFICE.

HARRY R. VAN DEVENTER, OF NEW YORK, N. Y., ASSIGNOR TO DUBILIER CONDENSER CORPORATION, OF NEW YORK, N. Y., A CORPORATION OF DELAWARE.

ELECTRICAL CONDENSER.

Application filed March 11, 1925. Serial No. 14,815.

This invention relates to electrical devices, and more particularly to electrical condensers.

An object of this invention is the production of a condenser, the component parts of which are exceedingly cheap and simple, the arrangement of the parts being such that the matter of replacement and repairs is reduced to a minimum.

10 Another object of this invention is the production of a condenser which is compact, durable and efficient, and so designed that it will withstand rough usage.

Another object of this invention is the production of a condenser so designed and constructed that it will not overheat and thus cause a break down.

20 A further object of this invention is the production of a condenser, having a unique terminal so constructed and arranged, and mounted within the wall of the casing, that undue heating around the terminal is avoided.

Yet a further object of this invention is the simple yet durable manner in which the 25 condenser casing is formed and mounted, all unnecessary parts being eliminated.

With these and other objects in view which 30 may be incident to my improvements, the invention consists in the parts and combinations to be hereinafter set forth and claimed, with the understanding that the several necessary elements comprising my invention, may be varied in construction, proportions and arrangement, without departing from the spirit 35 and scope of the appended claims.

In order to make my invention more clearly understood, I have shown in the accompanying drawings means for carrying the same into practical effect, without limiting the improvements in their useful applications to the particular constructions, which for the purpose of explanation, have been made the subject of illustration.

In the drawings forming a part of this 45 specification:

Figure 1 is a top plan view illustrating the condenser casing, the condenser sections and compression plate being shown in dotted lines;

50 Fig. 2 is a vertical sectional view taken on line 2-2 of Fig. 1;

Fig. 3 is an exploded perspective view of the terminal;

Fig. 4 is a diagrammatical view of a condenser stack, the condenser plates being connected in groups in parallel with intermediate condenser plates and dielectric sheets;

Fig. 5 is a vertical sectional view of a modified form;

Fig. 6 is a transverse sectional view taken on line 6-6 of Fig. 5; and

Fig. 7 is a diagrammatical illustration of a condenser stack connected in series.

Referring by numerals to the drawings, 1 represents a metallic base having a number 65 of apertures 2 distributed an equal distance apart adjacent to the edges. Mounted upon the base is a glass casing 3 having an integral right angular flange 4 in which are a number 70 of apertures 5. The casing is further provided with a central aperture 6 having a shoulder 7 formed therein, the object of which will hereinafter appear.

The flange 4 of the casing 3 bears against the base 1, the apertures 5 in the flange registering with the apertures 2 in the base. A gasket 8 is interposed between the flange and base, and studs 9 pass up through the registering apertures 2 and 5. Nuts 10 are mounted upon upwardly protruding ends of 80 the studs 9 and one of the studs 9 is further provided with a nut 11 adapted to clamp between itself and the nut 10 a lead, not shown.

Mounted upon the base 1 within the casing 3 are corresponding condenser sections 12. 85 Bearing upon these condenser sections is a plate 13 which supports like condenser sections 14 mounted immediately above the sections 12. Bearing upon the sections 14 is a plate 15 having its respective ends projecting 90 beyond the condenser sections and provided with apertures 16, which register with oppositely disposed apertures 17 in the base. Corresponding bolts 18 pass upward through the registering apertures 16 and 17 and are provided with nuts 19. By means of this construction a uniform pressure is exerted on the condenser sections.

A split sleeve 20, of any suitable non-conductive material, having a flange 21 and an 100 internal rib 22, encircles a terminal plug 23 having a groove 24 which receives the rib 22.

The sleeve 20, with the plug 23 mounted therein, is fitted into the aperture 6, the flange 24 on the sleeve bearing against the shoulder 7, the lower end of the sleeve bearing against 5 a gasket 25 fitted over the downwardly projecting end of the plug 23.

The plug 23 is threaded into a non-conducting sleeve 26, the upper end of which bears against the gasket 25. The sleeve 26 extends 10 downwardly through an aperture 27 in the plate 15 to a position slightly above the plate 13 sufficient to allow for expansion and contraction. A braided copper wire 28, which passes through the sleeve 26, connects 15 the plug 23 to the plate 13. The upper end of the plug projecting through the sleeve 20 is threaded to receive a nut 29, and upon the top of the plug is a set screw 30 for attaching a lead, not shown.

20 In Figs. 5 and 6 I have shown a modified form wherein the base 1 and casing 3 take a circular form in lieu of the form shown in Figs. 2 and 3, hence the plates 13 and 15 would also take a circular form in order to conform 25 with the configuration of the casing.

The difference involved is that in this form a greater number of condenser sections 12 may be employed, also the compression bolts 18 are interposed alternately between the condenser sections, which would tend to more 30 evenly distribute the pressure. In this form the non-conducting sleeve 26 is omitted. The terminal plug 23, which is connected to the plate 13 by a braided copper wire 28, has a 35 flange 31. A mica washer 32 is slipped over the plug 23, and bears against the flange 31. The plug 23 is passed up through the aperture 6, the washer 32 bearing against the under surface of the casing wall.

40 A mica washer 33 is fitted over the protruding end of the plug and bears against the outer surface of the casing wall. A nut 34 is threaded on the protruding end of the plug and bears against the washer 33. By tightening the nut 34, the terminal plug is secured 45 in place. Fitted on the protruding end of the terminal plug over the nut 34 is a nut 35 adapted to clamp between itself and the nut 33 a lead, not shown.

50 Figs. 4 and 7 are diagrammatical illustrations of two distinct types of condenser stacks, either of which may be employed in the construction of the condenser sections. The form shown in Fig. 4 consists of a plurality 55 of condenser plates 36 and dielectric sheets 37. The condenser plates are connected in groups 38 in conjunction with intermediate condenser plates and dielectric sheets. The form illustrated in Fig. 7 comprises a plurality 60 of condenser plates 39 and dielectric sheets 40 connected in series.

With the arrangement shown in Figure 4 some of the plates are isolated constituting in effect floating capacities, and if this arrangement is adapted for either the sections

12 or 14, the terminals of the groups 38 will be connected one to the plate 12 and the other to the plate 1, or the other to the plate 15, as the case may be.

The arrangement of the conductive plates 70 shown in Figures 4 and 7, however, is intended only as an example, as any desired method of connecting the conductive plates of the condenser may be employed.

While I have shown and described the preferred embodiment of my invention, I wish it to be understood that I do not confine myself to the precise details of construction herein set forth by way of illustration, as it is apparent that many changes and variations 80 may be made therein, by those skilled in the art, without departing from the spirit of the invention, or exceeding the scope of the appended claims.

Having thus described the various features 85 of my invention, what I claim as new and desire to secure by Letters Patent is:

1. In a condenser, a base, a casing mounted upon the base, a plurality of condenser sections mounted upon the base within the casing, a plate intermediate the condenser sections, a plate bearing against the upper tier of condenser sections, means for compressing the condenser sections, a terminal mounted in the wall of the casing, and a braided wire 95 connecting the terminal with the intermediate plate.

2. In a condenser, a base, a casing mounted upon the base, a plurality of condenser sections mounted within the casing in tiers, a 100 plate interposed between the tiers, the lower tier of condenser plates bearing against the base, a top plate bearing against the top tier, means between the base and top plate for exerting a pressure, a terminal in the wall of the casing, and a connection between the terminal and the intermediate plate.

3. In a condenser, a base, a casing mounted upon the base, a plurality of condenser sections mounted upon the base within the casing, an intermediate plate between the condenser sections, a top plate bearing against the condenser sections, means for exerting a pressure between the base and top plate, a terminal mounted in the wall of the casing, 115 a sleeve mounted upon the inner end of the terminal, a braided wire extending through the sleeve and connecting the terminal with the intermediate plate, and means upon the terminal for attaching a lead.

4. In a condenser, a base, a casing mounted on the base, a condenser in the casing in contact with the base, a plate overlying the condenser, means for connecting said plate directly to the base to compress the condenser, 125 a terminal carried by the casing and a connection between the condenser and said terminal passing through an opening in said plate.

5. An electrical condenser comprising a 130

casing, a body within the casing comprising a plurality of conductive members separated by dielectric material, terminal means for the condenser whereby the same may be connected in circuit, one of the terminal means comprising a terminal plug supported by the casing, a split sleeve encircling said plug, interlocking means between the sleeve and the

plug, threads upon the respective ends of the plug, a sleeve mounted upon one end of the 10 plug and extending into the condenser body, and a conductor passing through said sleeve.

Signed at New York, in the county of New York and State of New York, this 10th day of March A. D. 1925.

HARRY R. VAN DEVENTER.
